UNITED STATES PATENT OFFICE.

FRANCIS SABOT, OF PHILADELPHIA, PENNSYLVANIA, ASSIGNOR TO RUDOLPH SATTLER, OF CINCINNATI, OHIO, TRADING AS THE RUDOLPH SATTLER COMPANY.

EMBOSSING PRINTING-PRESS.

1,367,565.

Specification of Letters Patent.

Patented Feb. 8, 1921.

Application filed June 28, 1917. Serial No. 177,474.

To all whom it may concern:

Be it known that I, FRANCIS SABOT, a citizen of the United States, and resident of Philadelphia, county of Philadelphia, 5 and State of Pennsylvania, have invented an Improvement in Embossing Printing-Presses, of which the following is a specification.

The object of my invention is to provide 10 a suitable means, in an embossing printing press, for removing the surplus ink from the wiping web and returning it to the ink well; and further to provide means for treating the ink laden wiping web to a solvent 15 whereby the surplus ink is more easily removed therefrom and collected as above stated, and also leaving the paper web in condition whereby it may be used as a by-product for stock in paper making.

20 My object further, is to provide a protected source of solvent supply from which the solvent may be automatically fed to the solvent applying means (movable with the wiping web frame), so that only a small 25 quantity of volatile solvent is exposed at any moment, but whereby the applying means is replenished in a more or less continuous manner, to the end that the press may be operated for long periods without 30 danger of fire which would result from too large a quantity of solvent in exposed condition in the operative portions of the machine.

With these and other objects, hereinafter 35 set out, in view, my invention consists of certain constructions and combinations of parts fully described in the following specifications and more particularly defined in the claims.

40 My invention will be better understood by reference to the accompanying drawings, in which:—Figure 1 is a sectional elevation of an embossing printing press embodying my improvements; Fig. 2 is a cam detail for 45 operating the wiper; Fig. 3 is a cross sectional view of means for applying a solvent to the paper wiping web; Fig. 4 is a plan view of the same; Fig. 5 is an elevation of a portion of the solvent feeding 50 means; and Fig. 6 is a sectional view of the immediate means for removing the surplus ink from the web.

The general construction of embossing printing presses having automatic wiping 55 devices is well known in the art, and while

I do not in this application make claim to the machine broadly, nevertheless for imparting a better understanding of my improvements therein, I have shown in Fig. 1 a general view of the operative parts and 60 their relation to each other, and will now briefly describe the same. 2 is the main framing, 3 is the stamping plunger, and 4 is the die carriage and die secured therein. The die carriage is reciprocated horizontally, from the position shown, backward under the wiper pad 15 and to a position to receive ink by the ink applying roller 9, and thence forward again to the impression position shown. When the die is moved 65 backward to receive ink, the wiper frame and pad 15 are raised so that the paper wiping web 14 does not touch the die; but when the die has been inked and moved forward, the wiper pad 15 is moved downward into wiping position for pressing the paper web 14 into contact with the die as it passes beneath for causing the surplus ink upon its surface to be wiped off upon the web to leave the die clean except for the 70 ink in the engraved grooves, as in intaglio printing. The carriage and die 4 are reciprocated by the rocking lever 5 and links 6, 6, jointed together at 7, one of the links being hinged to the carriage and the other 75 to the lever 5. The hinge 7 has guide rollers which traverse the guideway 8, so that the links fold at the termination of the oscillation of the lever 5 to give a dwell to the carriage and die during the printing or 80 embossing operation. The inking roller is carried by levers 10 which are rocked by suitable means operated from the main shaft 34. In fact, all of the power emanates from 85 the main shaft, but it will not be necessary 90 to describe in detail the several instrumentalities employed, as these may be of any suitable construction so far as the utility of my invention is concerned. The means for raising and lowering the wiping pad is 95 shown in Figs. 1 and 2, and comprises a rocking lever 29 having at one end a link construction 30 which carries the wiping frame and pad 15, said lever having at its other end connection with a power applying 100 rod 32 guided at its upper end by the shaft 34 and hinged at its lower end to the aforesaid lever. The rod 32 has a roller 33 working in a cam groove 31 of a cam secured to 105 the said main shaft 34. This means recip-

rocates the wiping frame and pad at properly timed intervals, as will be understood.

The wiping web is of paper and wound in a roll 16, supported so as to be unwound therefrom as required. A friction strap 16^a weighted at 16^b applies a braking action to prevent spinning under the intermittent pull. The web 14 passes from the roll 16 over guide 17 and between rollers 18 and 18^a, 10 thence over a guide rod 19 on the wiper frame, thence under the wiper pad 15, thence upward and over the solvent applying roller 20, thence under the drag roller 21, thence over the scraping knife 25, and thence under 15 the guide 26 to the winding mandrel 27. The mandrel 27 is intermittently driven to properly feed the web through the machine in such manner that it is fed when the embossing is taking place and when the wiper 20 pad is out of action.

Referring to Fig. 6, it will be seen that the web 14 is bent over the scraping knife 25 at such an angle as to insure the surplus ink upon its under side being fully scraped off, but without abrasion of the paper. This is accomplished by having the lower portions of the roller 21 and the guide 26 below the scraping edge of the knife 25; or more particularly, it is essential that the 25 scraper edge be above the plane across the bottom portions of the guide parts 21 and 26. It is also important that the roller 21 shall put a drag upon the web so that a substantially uniform friction shall be put 30 upon the paper by the scraping knife, and this is accomplished by mounting the roller 21 upon the fixed rod 22 and applying a friction to the roller by an adjustable brake 23 having the tension screw 24. By adjusting the screw 24, any drag required may be 35 provided, more drag being desirable for narrow webs than for wide webs.

When the ink is scraped from the web 14 by the knife 25, it falls upon the inclined 45 chute 28 and is fed down to the ink well 13 (Fig. 1). The ink in the well 13 is supplied by the feed roller 12 and distributor roller 11 to the inking roller 9, which applies it to the die as before explained.

50 Considering now the solvent applying means, the roller 20 is loosely supported by its bearings 46 in open top boxes in a frame 44 secured to and moving with the wiper frame. Immediately below the roller 20 is 55 a solvent carrying means adapted to supply solvent to the roller 20, said means comprising a trough frame 35 having a longitudinal pocket in which strips of wick 36 are placed and which are kept in contact with the bottom of the roller 20. To one side of the wick pocket is a solvent receiving well 37 having small ports 38 leading from its bottom to the lower portion of the wick pocket (Figs. 3 and 4), and outside of the well 37 65 is an overflow chamber 39 which may re-

ceive any accidental overflow of solvent to remove it out of possible contact with the wicks 36. This trough frame 35 is adjustable vertically at 45 on the frame 44 and the extent of its vertical adjustment required may be had by adjusting screws 47. By this means, any desired pressure between the wicks and the roller 20 may be had. The solvent may be supplied to the well 37 by a pipe 40 leading downward from the 70 reservoir 41. The extent of feed may be adjusted by the sight-feed 42 having the usual adjusting nozzle; and the solvent may be completely shut off, when desired, by a valve 43 in the pipe 40. It is preferable that 75 the valve 43 be sufficiently low in pipe 40 that the space therein between said valve and the sight-feed device 42 will just fill the well 37 and saturate the webs, so that after the machine has been shut down, the valve 80 85 43 may be turned on full when starting up again without fear of overflowing of the device. While I do not restrict myself to any particular character of solvent, gasoline, turpentine or other free solvent for the 90 ink may be employed.

I will now describe the means for feeding the wiping web. As before stated, this is accomplished by imparting rotary motion to a mandrel 27 upon which the paper wiping web is wound and after it has been scraped of the surplus ink. The construction of mandrel operating means may be similar to those heretofore employed in a machine of this character, for example as 100 shown in Letters Patent No. 951,481, dated March 8, 1910, in which the mandrel, corresponding to mandrel 27 in this application, is intermittently rotated by power transmitting connections of which sprocket chain 68 105 is a part. So far as my present invention is concerned, the mandrel 27 may be understood as an intermittently driven paper web winding mandrel of any suitable construction which is adapted for the purpose of 110 pulling upon the web to maintain it taut and wind it into a roll with a speed commensurate with the feeding of the web by the rolls 18. When the mandrel is filled with the paper web, the paper may be removed and the operation repeated. In machines of this class, the said power transmitting connections are of such nature that an intermittent motion is imparted to the chain 68, so that the winding mandrel of 115 120 the wiping web is also given an intermittent rotation; but as such devices are well known and do not form a part of the present invention, no detailed description of them will be necessary.

125 The winding action of the mandrel causes a given length of clean web to be drawn under the wiping pad 15, and at the same time causes the ink carrying web 14 to pass over the solvent applying roller 20 and the scrap- 130

ing knife 25. This having been done, and the carriage and die 4 having been moved under the wiping pad (but without touching the web) to a position to receive ink 5 from the roller 9 when moved forward, the wiping pad 15 is moved downwardly by the action of cam 31 (Fig. 2), and the carriage and die 4 moving forward cause the die to wipe its inked surface upon the under surface of the web 14 below the said wiping pad 15.

By my improvements the paper web containing the ink wiped from the die is subjected to a solvent by the roller 20 and associated means in such a manner that the ink is brought to an excellent condition by which it is easily removed by the scraper 25 over which the paper is drawn so that the valuable ink may be collected without 20 moving the fiber of the paper. In this manner, a material quantity of the ink is returned for use and a minimum quantity is left upon the web, the latter being sufficiently meager as not to objectionably 25 impair the paper stock wound upon the mandrel 27, and consequently not only is there economy in ink, but the by-product of the waste paper is a material factor of saving.

While I have described my improvements 30 in the form which I have employed commercially and found well suited to the requirements of the invention, nevertheless I do not confine or restrict myself to the details, as these are susceptible of modifications and 35 changes within the scope of mechanical skill without departing from the spirit of the invention.

Having now described my invention, what I claim as new and desire to secure by Letters Patent, is:—

1. In means for applying solvent and the removal of ink from a wiping web of an embossing printing press, employing a vertically reciprocating frame having a wiping 45 pad under which the web passes, a stationary scraper for removing the surplus ink from the wiping web, combined with a solvent applying device movable with the frame and its pad and adapted to apply a solvent to the inked web before it reaches the scraper, said solvent applying device and scraper being greatly separated to allow a sufficient interval of time for the ink to be softened before removal by the scraper.

55 2. Means in the embossing printing press for removing ink from the wiping web thereof, consisting of a roller over which the inked web is drawn, a reservoir for solvent, a wick extending upward from the solvent 50 reservoir and in contact with the roller for applying solvent thereto in a restricted but uniform manner, and a scraper arranged at the delivery side of the roller for removing the surplus ink from the web,

said scraper independently supported with 65 reference to the roller and separated a considerable distance from the roller to provide a sufficient interval of time for the solvent to soften the ink before its removal.

3. An embossing printing press provided with die and pressing devices, ink applying 70 devices, a wiping web and a pad for pressing the wiping web upon the inked die for wiping it, combined with a scraper for scraping the surplus ink from the inked web and means at the delivery side of the pad 75 for applying a solvent to the inked web before it reaches the scraper, said means consisting of a roller over which the web passes, a vessel below the roller having a wick chamber and a solvent chamber in communication with each other at their lower parts, a wick in the wick chamber pressing upon the underside of the roller, and means to feed solvent to the solvent chamber, said means for applying solvent to the inked 80 web and the scraping means being separated at a considerable distance apart to provide a sufficient interval of time for the solvent to soften the ink before its removal.

4. In means for removing ink from a 90 wiping web of an embossing printing press, a scraper over which the inked wiping web is drawn, combined with separate guides upon opposite sides of the scraper for the web for bending the paper web over the edge 95 of the scraper to insure removal of the surplus ink without abrasion of the paper surfaces, the forward guide consisting of a single roller and an adjustable friction applying means acting to apply friction directly 100 to the roller to prevent free rotation of the roller and adjust the extent of drag upon the web.

5. Means in an embossing printing press for removing ink from the wiping web 105 thereof, consisting of a roller over which the inked web is drawn, a reservoir for solvent, a wick extending upward from the solvent reservoir and in contact with the roller for applying solvent thereto in a restricted but uniform manner, said wick and reservoir adjustable vertically relatively to the roller, and a scraper arranged at the delivery side of the roller for removing the surplus ink from the web, said scraper independently 110 supported with reference to the roller and separated a considerable distance from the roller to provide a sufficient interval of time for the solvent to soften the ink before its removal.

115 In testimony of which invention I hereunto set my hand.

FRANCIS SABOT.
